CLAIM

The ornamental design for a yellow jacket trap, as shown and described.

DESCRIPTION

FIG. 1 is a perspective view of a yellow jacket trap embodying my new design.

FIG. 2 is a top plan view of the yellow jacket trap of FIG. 1.

FIG. 3 is a rear elevational view of the yellow jacket trap of FIG. 1.

FIG. 4 is a left end elevational view of the yellow jacket trap of FIG. 1.

FIG. 5 is a bottom plan view of the yellow jacket trap of FIG. 1.

The front, not shown, is like the rear shown in FIGS. 1 and 3.

FIG. 2.

FIG. 1.

FIG. 3.

FIG. 4.

FIG. 5.
